(57) **CLAIM**

The ornamental design for, a rear cover for a motor scooter, as shown and described.

DESCRIPTION

FIG. 1 is a first perspective view of a rear cover for a motor scooter, showing our new design;

FIG. 2 is a front elevation view thereof;

FIG. 3 is a top plan view thereof;

FIG. 4 is a right side elevation view thereof; and,

FIG. 5 is a left side elevation view thereof.

The broken lines are for illustrative purposes only and form

no part of the claimed design.
